UNITED STATES PATENT OFFICE.

THOMAS YOUNG, OF BRADFORD, PENNSYLVANIA.

HEATING-STOVE.

SPECIFICATION forming part of Letters Patent No. 743,370, dated November 3, 1903.

Application filed August 5, 1902. Serial No. 118,521. (No model.)

To all whom it may concern:

Be it known that I, THOMAS YOUNG, a citizen of the United States, residing at Bradford, in the county of McKean and State of Pennsylvania, have invented a new and useful Heating-Stove, of which the following is a specification.

This invention relates to stoves and furnaces, and it has special reference to heating-stoves of that class in which gas, oil, or gaseous vapor is used as a fuel and in which the products of combustion are carried from the upper part of the combustion-chamber through flues back into the lower part of the combustion-chamber in order that circulation may be established, which shall assist in promoting the combustion of products which otherwise might escape into the room or apartment where the device is being used.

My present invention has for its object to provide a stove of this class having an open front and an adjustable foot-rest.

A further object of my invention is to simplify the general construction and arrangement of parts whereby a device shall be produced possessing superior advantages in point of simplicity, durability, and general efficiency.

With these ends in view the invention consists in the improved construction, arrangement, and combination of parts which will be hereinafter fully described, and particularly pointed out in the claims.

In the accompanying drawings, Figure 1 is a vertical sectional view of a stove constructed in accordance with my invention. Fig. 2 is a horizontal sectional view of the same. Fig. 3 is a perspective detail view of the adjustable foot-rest of the device.

Corresponding parts in the several figures are indicated by like numerals of reference.

In the accompanying drawings I have illustrated a stove with a burner adapted for the consumption of liquid fuel, such as oil, or gas.

The body of my improved stove is composed of a casing 1, which may be of any desired size and shape. In the present instance it is composed of a rectangular box, the bottom of which, 2, is extended forwardly to form a hearth provided with flanges 3 at the sides and in front. The front side 4 of the casing is cut away at its lower end to form an open-

ing 5 directly above the hearth. The bottom of the stove-casing is provided with a rectangular opening, through which extends a flue 6, the upper end of which is tightly connected with said bottom and extended upwardly, so as to form a flange 7. Another flange 8, secured to the bottom of the stove, surrounds the flange 7, and the space between the said two flanges forms a channel or receptacle 9, slightly above which is arranged a burner 10, composed of sides 11 and ends 12, which may be bent from a single pipe or which, as in the drawings, may be composed of independent pipes connected at their corners by elbows 13. The burner-pipes 11 and 12 are perforated, as shown at 14, and the end pipes 12 are connected with the sides of the stove-casing by extensions, one of which, 15, is simply a supporting device, while the other extension, 16, forms an inlet-pipe through which liquid fuel or gas may be supplied to the burner. The rear part of the stove-casing is provided with a curved deflector 17, extending from the rear part of the flange 8 and almost to the top of the stove-casing.

The lower end of the flue 6 is connected with a horizontally-disposed flue 18, arranged under the body of the stove and having at its rear end an upward extension 19, the upper end of which has a forward extension 20, which in turn is connected by a short flue 21 with the top of the stove-casing. The lower end of the flue 19 is provided with an inverted funnel 22, forming an air-inlet whereby the draft is accelerated, the air entering through said funnel assisting in creating a downward suction through the pipe 19, as will be readily understood, the said funnel terminating in a pipe which is bent in a forward direction, as clearly seen in Fig. 1 of the drawings.

The hearth of the stove is provided at its front corners with uprights 23, having bearings for a rocking plate 24, the lower edge of which is provided with stops 25, adapted to abut against the front sides of the uprights 23. The rocking plate 24 is provided with slots 26 to receive the arms of a U-shaped plate 27, the front or bent end of which supports the foot-rest proper, 29. It will be seen that by properly adjusting the U-shaped support 27 the foot-rest may be disposed at any desired distance from the hearth-opening, while at

any position to which it is adjusted the supporting device is capable of swinging by means of the supporting rocking plate 24, thus enabling a person sitting in front of the 5 stove to adjust his feet comfortably with relation thereto.

The operation of this invention will be readily understood. When oil or other liquid fuel is to be used, a small quantity of such 10 oil or other liquid fuel may be placed in the channel or receptacle 9 and ignited, thus heating the burner, which is disposed above said channel. When the burner has been sufficiently heated, the oil entering the same 15 will be vaporized, and on issuing through the perforations 14 will be ignited. The smoke and products of combustion will ascend through the flue 21 and be guided through the flues 20, 19, 18, and 6 back into the combustion-chamber, where a nearly-complete combustion will take place, the same being assisted by air admitted through the funnel 22 and at the front end of the flue 18, at which latter point the admission of air is 20 preferably regulated by means of a slide 30. Unconsumed air and products of combustion may escape to the open through the hearth-opening 5.

Gas may be consumed in place of liquid 25 fuel by using a burner constructed exactly as herein described; but it will be understood that the construction of the burner may be modified to any extent within the scope of my invention.

30 I have in the foregoing described the preferred form of my invention; but I would have it understood that I do not limit myself as regards the details of such construction, but reserve the right to any changes and 35 modifications which may be resorted to without departing from the spirit of my invention. It will be furthermore understood that the application of the invention is by no means necessarily confined to stoves, either 40 generally or of the particular pattern herein shown and described, it being applicable with equally advantageous results to all kinds of locomotive, stationary, or movable 45 boilers—in fact, to every kind of furnace or 50 boiler-heater.

Having thus described my invention, I claim and desire to secure by Letters Patent of the United States—

1. In a stove of the class described, a casing 55 having a top and a bottom plate, an exteriorly-disposed return-flue connecting the top plate with the bottom plate, an extension of said return-flue projecting forwardly below the stove, and a slide at the front end of said 60 extension to regulate the admission of air.

2. In a stove of the class described, a casing, a plate forming the bottom of said casing and extended forwardly to form an open hearth through which air may be admitted 65 into the combustion-chamber, a return-flue connecting the top of the casing with the bottom of the casing, a forward extension of said

return-flue, and means for regulating the admission of air into said flue.

3. In a stove of the class described, a casing 70 connecting the top of said casing with the bottom of the same, and an inverted funnel connected with the lower part of said return-flue.

4. The herein-described stove-casing having 75 its bottom extended and its front cut away to form an open hearth and provided with uprights at the front corners of said hearth, in combination with a rocking plate mounted adjustably in said uprights, and a 80 foot-rest adjustably connected with said rocking plate, substantially as set forth.

5. In a stove of the class described, a casing 85 having a forwardly-extended bottom plate and a front plate provided with an opening coöperating with the forwardly-extending bottom plate to form an open hearth, in combination with a foot-rest, a rocking plate supporting said foot-rest, and supporting means for said rocking plate, said supporting means 90 being mounted upon the forwardly-extending bottom plate of the casing.

6. In a stove of the class described, a casing 95 having a bottom plate provided with an opening, a flue extending through said opening and tightly connected therewith, a flange 100 surrounding said flue and forming a channel or receptacle, a burner corresponding in shape with, and disposed slightly above said channel, and a flue connecting the lower end of the flue extending through the bottom of the stove-casing with an opening in the top of said stove-casing.

7. In a return-flue stove having a forwardly-extended open hearth, a bottom flue 105 extended upwardly through the stove-bottom and tightly connected therewith, a flange surrounding said flue and forming a channel or receptacle, a burner disposed slightly above said channel and having extensions 110 projecting through and supported by the sides of the stove-casing, one of said extensions forming an inlet for the fuel, and a flue connecting the lower end of the bottom flue with an opening in the top of the stove-casing. 115

8. The combination with a stove having a forwardly-extended open hearth, of a rocking plate, slots in said plate, a support extending adjustably through said slot and a foot-rest mounted upon said support, substantially as set forth. 120

9. The combination with a stove having a forwardly-extended open hearth, of a rocking plate, slots in said plate, means for limiting the movement of said rocking plate, a 125 support connected adjustably with said rocking plate, and a foot-rest mounted upon said support, substantially as set forth.

10. A return-flue stove having a forwardly-extended open hearth, in combination with a 130 rocking plate carrying a longitudinally-adjustable foot-rest, and means for limiting the rocking movement of said plate, substantially as set forth.

11. A heater comprising a combustion-chamber having a smoke-exit, an opening in the bottom of said combustion-chamber, a return-flue connected with the smoke-exit in the upper part of the combustion-chamber and connecting said smoke-exit with the inlet in the bottom thereof, said flue being extended past said inlet and provided with a slide or damper at its front end, substantially as set forth.

12. A heater comprising a combustion-chamber having a smoke-exit, an opening in the bottom of said combustion-chamber, a return-flue connected with the smoke-exit in the upper part of the combustion-chamber and

connecting said smoke-exit with the inlet in the bottom thereof, said flue being extended past said inlet and provided with a slide forming a damper in its front end, and an auxiliary air-inlet at the lower end of the vertical portion of said return-flue, substantially as set forth. 20

In testimony that I claim the foregoing as my own I have hereto affixed my signature in the presence of two witnesses.

THOMAS YOUNG.
